UNITED STATES PATENT OFFICE

LEONHART F. SOMMERFELD, OF CANTON, KANSAS, ASSIGNOR OF ONE-THIRD TO
H. G. ROLF, OF MCPHERSON, KANSAS

ALFALFA LOADER

Application filed June 11, 1930. Serial No. 460,439.

This invention relates to an alfalfa loader and has for its prime object to provide a wheeled structure for picking up alfalfa from the ground and elevating it for delivery to the side of the wheeled structure on to a rack, wagon or the like.

Another very important object of the invention resides in the provision of an endless conveyor structure for moving the alfalfa having a portion thereof disposed on an incline with elongated plates spring pressed against the upper run of the elevating portions.

A still further very important object of the invention resides in the provision of an alfalfa loader of this nature which is exceedingly simple in its construction, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a loader embodying the features of my invention,

Figure 2 is a side elevation thereof,

Figure 3 is a longitudinal section taken substantially on the line 3—3 of Figure 1,

Figure 4 is a transverse section taken substantially on the line 4—4 of Figure 1,

Figure 5 is another transverse section showing particularly the endless conveyor,

Figure 6 is a detail longitudinal section taken substantially on the line 6—6 of Figure 1,

Figure 7 is a perspective view showing one end of one of the elongated pressure plates,

Figure 8 is a sectional view taken on the line 8—8 of Figure 2,

Figure 9 is a detail view of one of the guides, and

Figure 10 is a detail view of the clutch actuating member.

Referring to the drawings in detail it will be seen that the wheeled frame comprises

a pair of longitudinal members 5 and 6 both of which are offset upwardly at their front ends to provide extensions 7 and 8 respectively the front extremities of which are mounted on the front wheeled truck 9. The side 5 is longer than the side 6 and extends rearwardly terminating in a lateral extension 10, the side member 11 has an intermediate portion engaged as at 12 with the end of the extension 10 and the forward portion of this side member 11 inclines downwardly and forwardly as at 14.

On the rear end portion of the side member 11 is an adjustable weight element 15. A transverse conveyor frame comprises a horizontal portion 17 and an inclined portion 18. The extension 14 is secured to the frame portion 17 and a member 19 has an inclined extension 20 secured to the frame portion 17. An axle 21 is journaled through the member 19, the side portion 11, and the side 5 and rotates with a wheel 22 thereon, inside of the side member 5.

Another member 23 is rotatable on the other end of the axle shaft 21 to the outer side of the member 19. A brace rod 24 is disposed between the side member 11 and the rear extremity of the member 19. A gear 25 is rotatable on the axis shaft 21 and has a clutch segment 26 fixed thereto for engagement by a sliding clutch segment 27 splined on the axle shaft and actuatable by a rockable cam element 28 having a crank 29 controlled by a rod 30 leading to a lever 31 on the portion 8 of the side member 6.

A seat 33 is mounted on a cross member 34 on the extensions 7 and 8 so that the lever 31 is easily accessible.

A plurality of ground engaging guides are denoted generally by the letter G and comprise bottom portions 36 which merge into upwardly and rearwardly inclined extensions 37. At the rear ends the ground engaging portions 36 merge into upstanding portions 37 attached to a rod 39 in brackets 40 secured to the front of the horizontal frame portion 17.

A beater B is formed with an elongated hub 40 having a plurality of fingers 41 radiating therefrom a group between each pair

100

of guides G and to the outer sides of the endmost guides G. The hub 40 is mounted on a shaft 42 journalled in brackets 43 projecting from the front of the frame member 17.

A beveled pinion 45 on the shaft 42 meshes with a beveled pinion 46 on a shaft 47 which has a universal coupling 48 with a shaft 49 journalled in a bracket 50 and having a pinion 51 thereon in mesh with the gear 25.

An endless belt 52 is trained over rollers 53, 54 and 55 in the frame members 17 and 18 and guide rollers 56 engage the side edge portions of the endless belt immediately above the roller 54. The roller 54 is on the shaft 47. The shaft 47 is operatively connected with the roller 55 by chain and sprocket mechanism 59. A plurality of cross slats 60' are provided on the endless belt.

A plurality of pressure elongated plates 60 have their lower ends curved as at 61 and have rods 62 extending therefrom to be slideable through inverted U-shaped frames 64 and springs 65 are disposed about the rods 62 to press the plates 60 downwardly on the upper runs of the endless belt in the frame portion 18 to keep the alfalfa thereon in its upward movement.

The frames 64 have their ends straddling the frame portion 18 and secured thereto. From the above detailed description it will be seen that this machine may be pulled along by any suitable draft means and will pick up the alfalfa from the ground and the beater 25 will throw the alfalfa up along the inclined portions 37 of the guide G on to the horizontal portion of the upper run of the endless belt so as to be conveyed upwardly to the side of this machine and dumped on to a rack, 40 wagon or the like.

It is thought that the construction, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A hay or grain loader of the class described comprising a wheel supported structure, a transversely disposed endless conveyor mechanism thereon and including a horizontal lower part and an upwardly and outwardly elevated portion, a plurality of rake members

extending forwardly from the horizontal portion and each including a horizontal ground engaging part and an upwardly and rearwardly extending part connected at its front end with the front end of the ground engaging part, said rake members being spaced apart, a drum rotatably supported between the upper and lower portions of the rake members, fingers on the drum arranged in groups, each group located between a pair of rake members, inverted U-shaped members having the extremities of the limbs connected to the side parts of the elevated part of the conveyor mechanism, a plurality of strips located above the said elevated portion of the conveyor mechanism and having their lower ends curving upwardly, rods connecting the said strips and passing through the bight portions of the U-shaped members, springs on the rods between the strips and said bight portions and means for rotating the drum and for actuating the conveying mechanism from one of the ground wheels of the structure.

In testimony whereof I affix my signature. 90
LEONHART F. SOMMERFELD.
